UNITED STATES PATENT OFFICE.

HENRY KLEMAN, OF PITTSBURGH, PENNSYLVANIA, ASSIGNOR OF ONE-HALF TO
EDWARD MARTIN, OF PITTSBURGH, PENNSYLVANIA.

SMOKE-CONSUMER.

1,139,194.

Specification of Letters Patent. Patented May 11, 1915.

Application filed August 29, 1910. Serial No. 579,519.

To all whom it may concern:

Be it known that I, HENRY KLEMAN, a resident of Pittsburgh, in the county of Allegheny and State of Pennsylvania, have 5 invented a new and useful Improvement in Smoke-Consumers, of which the following is a full, clear, and exact description, reference being had to the accompanying drawings, forming part of this specification, in which—

10 Figure 1 is a vertical transverse section through one form of apparatus embodying my invention. Fig. 2 is a sectional plan view on the line II—II of Fig. 1. Fig. 3 is a perspective view partially in section, on an 15 enlarged scale of the cooler and separator. Fig. 4 is a vertical section through a modified form of cooler and separator. Fig. 5 is a side elevation partially in section of another form of cooler and separator. Fig. 20 6 is a sectional view of another modified form of cooler, and Fig. 7 is a detail sectional view on the line VII—VII of Fig. 1.

25 My invention relates to the class of smoke consumers wherein the particles of soot, dust and unconsumed products are mechanically separated from the hot air and gases, by forcing the smoke from the flue through a liquid bath.

30 The object of my invention is to provide a cheap and simple apparatus in which the smoke is forced through a cooler to condense the gases, after which they are forced through a separator to remove all of the heavy matter, and after which they are 35 again passed into the furnace with a suitable amount of oxygen so that the gases will be consumed.

Another object of my invention is to collect all of the tar, and unconsumed matter, 40 which is contained in the gases and which can be collected and utilized for various by-products.

Still another object of my invention is to utilize the heat of the gases to heat the 45 water at the same time that the gases are cooling and condensing, which can be used for any desirable purpose.

The precise nature of my invention will be best understood by reference to the accompanying drawings, which will now be described, it being premised, however, that various changes may be made in the details 50 of construction and general arrangement of the parts without departing from the spirit

and scope of my invention, as defined in the 55 appended claims.

In the drawings, the numeral 2 represents a stack leading from a smoke box 3 of a boiler 4, having the usual fire box or combustion chamber 5 and an ash pit 6.

60 6^a are doors pivotally mounted in the ash pit, and connected to each is a lever 6^b. These levers are connected to each other by a link. 6^c is a hand lever connected to one of said levers and is arranged to close both 65 doors when the ash pit is to be cleaned.

7 is a pipe leading from the stack 2 to a fan 8.

9 is a gate valve in the pipe 7, and 10 is a butterfly valve in the stack 2 above the connection between the pipe 7 and the stack.

11 is a pipe leading from the fan 8 to a coil of pipes 12 in a cooler 13. In Fig. 1, I have illustrated the cooler 13 of cylindrical form, and contained in the central portion 75 thereof is a separator chamber 14, containing an agitator 15, and 16 is a pipe connected to the cooling coil 12 and a rectangular pipe 17 which is in communication with the separator 15. The agitator 15 is 80 supported slightly above the bottom of the separating chamber 14, and the bottom of this agitator is perforated as indicated at 18.

19 is a curved perforated shield or deflector, one end of which is secured to the 85 bottom of the agitator for the purpose hereinafter described.

21 is a return pipe from the separator chamber 14 to a receptacle 22 in the upper portion of the ash pit 6, which is provided 90 with baffles 23 for the purpose hereinafter described.

24 is a butterfly valve in the pipe 21 and is adapted to be closed to cut off a portion of the gases from the separator 14.

95 25 is a Y connection in the pipe 21, two ends of which are connected to said pipe, the third end extending rearwardly, and to which is connected a nozzle 26. 27 is a slide on this end of the Y and is arranged to be 100 moved back and forth by means of the hand lever 28 to open and close the opening 29 between the end of the Y and the nozzle 26.

30 is a small pipe leading from the pipe 11 into the rear end of the nozzle 26, and is 105 provided with a hand valve 31 to open and close communication between the nozzle and the pipe 11.

32 is an air pipe leading from a fan 33 to the nozzle 26 and in the rear of the end of the pipe 30.

34 is a water supply pipe, and connected 5 to this pipe 34 is a valve controlled inlet pipe 35 to the interior of the separator chamber 14.

36 is a valve controlled inlet pipe from 10 the pipe 34 to the interior of the cooler 13, and 37 is a valve controlled spray pipe leading from the pipe 34 into the upper portion of the separator chamber 14, which is arranged to spray the gases passing from the separator chamber 14 to the fire box.

15 38 is a valve controlled overflow from the cooler 13 which may extend to a pump arranged to supply water to the boiler 4, or to any other point where it is desired to utilize the heated water.

20 39 is an overflow pipe from the separator chamber 14 which is always open, and is of sufficient area to maintain the level of the water slightly above the bottom of the agitator 15 as indicated in Fig. 1.

25 40 is a valve controlled pipe leading from the bottom of the chamber 14 to the overflow pipe 39, and is adapted to drain off the contents of the separator chamber 14 through the pipe 39, which may be connected 30 to a suitable tank in which the collected matter from the separator chamber may be retained, and which may afterward be collected and used for the manufacture of various by-products.

35 41 is a water gage connected to the cooling chamber 14 to indicate the height of the water within said chamber.

42 is a screen in the pipe 7 and adjacent to the opening to the fan 8, and 43 is a 40 pipe leading from the pipe 7 to a container 44, which is arranged to receive cinders, etc., which will be deflected by means of the screen 42.

45 is a gate valve in the bottom of the 45 container 44, and 46 is a butterfly valve in the pipe 43. When it is desired to empty the container 44, the butterfly valve 46 is closed, and the valve 45 is opened and after the container 44 has been emptied, the valve 50 45 is closed and the butterfly valve 46 is opened to permit the cinders, etc., to fall into said container.

47 is a steam gage connected to the upper portion of the chamber 13 for indicating the pressure within said chamber. 48 is a valve controlled flue leading from the ash pit to the fire box.

The operation is as follows: Fire is first started in the fire box 5, the valve 10 to the 60 stack 2 being closed, and the gate valve 9 being opened. The fan 8 being started to draw air from the ash pit, the door of which may be opened for a short time, a certain amount of air will be drawn from 65 the chamber 14. The fan 33 is also in oper-

ation at this time which will force air through the nozzle 26 and pipe 21 to the box 22, which will be deflected by means of the baffles 23 across the bottom of the grate bars. The smoke passes through the pipes 7 and 11 and the cooling coils 12 to the agitator 15 through the medium of the pipes 16 and 17. The current of gas and smoke passing through the agitator 15 will vibrate the shield 19, some of it passing around the shield and some of it through the orifice therein, and then passing out through the water in the bottom of the agitator and the orifices 18 to the receiving chamber, then through pipe 21 back to the fire box. The impact of the smoke and gas against the shoulder will depress the free end and partially submerge it in the water in the agitator, and the spring of the metal will return it against the current of the smoke 80 and gas. The current of smoke and gas and the spring of the metal will constantly vibrate the shield which will separate the water and gas, thereby preventing the gas from passing through the separator in large 90 globules which will thoroughly wash the heavy matter from the gas. If it is desired, the slide 27 can be moved back as indicated in Fig. 1, and the valve 31 opened, which will permit some of the gas to escape 95 through the nozzle 26, which will draw air through the opening 29 and be properly mixed so as to supply sufficient oxygen with the gas during its passage to the fire box. If desired, the valve 31 and the opening 29 100 can be closed, in which case the fan 33 will supply sufficient oxygen to the gas passing through the pipe 21 to the fire box to form perfect combustion. The gas in passing 105 through the cooling coils 12 will be cooled down which will condense the gases, and which will in turn heat the water in the chamber 13, which can be used as previously described. The spray pipe 37 leading into 110 the upper portion of the chamber 14 will further cool the gases after they have passed through the separator. The gases while passing through the water and the separator chamber 14 will be thoroughly washed, which will remove all of the soot and other 115 matter which will be deposited in the bottom of said chamber, and which can afterward be drawn off to be used as heretofore described.

In Fig. 4, I have illustrated a steam drum 120 49, which is connected to the upper portion of the chamber 13, and through which steam may be drawn for any suitable purpose.

In Fig. 5, I have shown a modification in which I have used all of the same reference 125 numerals with the letter "a" affixed, and in which case, I have shown the receiving chamber and cooler separated from each other, with the fan placed between the cooler and the separating chamber. By using a 130

construction of this character, the fan will be kept comparatively cool, as all of the gases, etc., will be cooled before their passage through the fan.

5 In Fig. 6, I have shown a further modification of a cooling chamber in which I have shown a tank having an upper and lower chamber 50 and 51 connected by means of vertical pipes 52, through which the gases 10 pass. In this case, the water for cooling the gases is contained in the chamber 53 between the heads.

10 The advantages of my invention result from the provision of means for thoroughly 15 cooling and washing the gases from the furnace, to which may be added the proper amount of oxygen, which is then passed to the furnace for re-consumption.

Another object of my invention is to provide 20 means for collecting the heavy matter in the gases and which can afterward be drawn off and utilized for manufacturing various by-products. Further in the provision of means for heating water by means 25 of the hot gases which can be used as feed water for the boiler or for any other purpose.

I claim:

1. A smoke consuming system, comprising 30 a furnace having a grate, a stack, an offtake pipe from the furnace stack, an inlet pipe to the air space below the grate, a fan to draw the gas from the stack to the offtake pipe and force it through the inlet, a gas cooling 35 coil between the offtake pipe and the inlet pipe, a tank containing water surrounding the coil, a direct connection between the offtake pipe and the inlet pipe in back of the fan for returning a portion of the gases to 40 the furnace, said direct connection leading from the offtake pipe in front of the cooling coil, and means to supply oxygen to the inlet pipe; substantially as described.

2. A smoke consuming system, comprising 45 a furnace having a grate, a stack, an offtake pipe from the stack of the furnace, an inlet pipe to the air space below the grate, a fan to draw the gas from the stack through the offtake pipe and force it through the inlet 50 pipe, a gas cooling coil between the offtake pipe and the inlet pipe, a tank containing water surrounding said coil, means for separating the heavy matter from the gases after 55 they have passed through the cooling coil, a direct connection between the offtake pipe

and the inlet pipe in back of the fan for returning a portion of the gases to the furnace, said direct connection leading from the offtake pipe in front of the cooling coil, and means to supply oxygen to the inlet pipe to 60 mix the oxygen with the gas from the direct connection and the gas which is passed through the cooling coil; substantially as described.

3. A smoke consuming system, comprising 65 a furnace having a grate, a stack, an offtake pipe from the stack, an inlet pipe to the air space below the grate, a fan to draw the gas from the stack through the offtake pipe and force it through the inlet pipe, a gas cooling 70 coil between the offtake pipe and the inlet pipe, a tank containing water surrounding said coil, a direct connection between the offtake pipe and the inlet pipe for returning a portion of the gases to the furnace, said direct connection leading from the offtake pipe in front of the cooling coil, and an injector 75 for feeding oxygen to the inlet pipe and for drawing the hot gases through the by-pass, the oxygen, hot gases and the gases from the 80 cooling coil mixing within the inlet pipe before entering the air chamber below the grate; substantially as described.

4. A smoke consuming system, comprising 85 a furnace having a grate, a stack, an offtake pipe from the stack, an inlet pipe to the air space below the grate, a fan to draw the gas from the stack through the offtake pipe and force it through the inlet pipe, a gas cooling 90 coil between the offtake pipe and the inlet pipe, a tank containing water surrounding said coil, a direct connection between the offtake pipe and the inlet pipe for returning a portion of the gases to the furnace, said direct connection leading from the offtake pipe 95 in front of the cooling coil, an injector for feeding oxygen to the inlet pipe and for drawing the hot gases through the by-pass, the oxygen, hot gases and the gases from the 100 cooling coil mixing within the inlet pipe before entering the air chamber below the grate, and a connection for feeding some of said gases to the combustion chamber of the furnace; substantially as described.

In testimony whereof, I have hereunto set 105 my hand.

HENRY KLEMAN.
